HOLDER FOR ERASER RUBBER, PENCIL, OR
THE LIKE

Max Vogel, Bridgeport, Conn.

Application March 12, 1940, Serial No. 323,537

3 Claims. (Cl. 120—36)

The present invention relates to improvement in holder for eraser rubber, pencil, or the like, and has for an object to provide a device of this character in which a length of gradually usable material, such as eraser rubber, and pencil material, such as graphite, crayon, or the like may be carried, so as to support and protect it and at the same time provide a convenient manipulating handle. Another object of the invention is to provide a strip of eraser rubber, pencil material, or other substantially equivalent gradually usable substance, to be cooperatively supported in the holder, and which is of special form to cooperate with the holding means of the holder, to the end that such material will be reliably held in place without the necessity for subjecting it to excessive distortion or squeezing, which in the case of the eraser rubber is apt to cause quick deterioration, and in the case of pencil material is apt to cause breakage.

Another object of the invention is to provide a holder in which the holding means is so designed that the length of the material held thereby may be unlimited as to length, and to this end it is particularly proposed to provide a longitudinally split retaining clip member open at both ends so that the material being held will not be limited in length by the length of the clip member. Another object is to provide a holder which will adapt itself in principle to various shapes, depending upon the particular design desired, or the material being held, the invention being equally adapted to incorporation in structures of flat cross-section, either rectangular or oval, and square, circular and polygonal cross-section.

With the above and other objects in view, embodiments of the invention are shown in the accompanying drawing, and these embodiments will be hereinafter more fully described with reference thereto, and the invention will be finally pointed out in the claims.

In the drawing:

Fig. 1 is a perspective view of a holder according to the exemplary illustrated embodiment of the invention, and showing an eraser rubber held therein.

Fig. 2 is a perspective view of the open ended retaining clip member, shown in detached open relation.

Fig. 3 is a perspective view showing the eraser rubber strip engaged by the retaining clip member, and partially inserted into the outer casing of the holder.

Fig. 4 is a longitudinal sectional view.

Fig. 5 is a front end elevation.

Fig. 6 is a longitudinal sectional view of a modified form of the invention in which the holder is of circular cross-section, and showing a pencil strip supported in one end, and an eraser strip supported in the other end.

Fig. 7 is a front end elevation from the pencil opening end.

Fig. 8 is a transverse sectional view, taken along the line 8—8 of Fig. 6.

Fig. 9 is a transverse sectional view taken along the line 9—9 of Fig. 6.

Fig. 10 is a perspective view of the end portions of the case employed in the modification shown in Fig. 6.

Fig. 11 is a side elevation of the split tube retainer member employed in the modification shown in Fig. 6, the same being shown in its detached expanded relation.

Fig. 12 is a fragmentary longitudinal sectional view of a modified form of the invention, as shown in Figs. 1 to 5, and in which the grooves provided upon the eraser rubber element are in staggered relation at each side.

Similar reference characters indicate corresponding parts throughout the several figures of the drawing.

Referring to the drawing, particularly to Figs. 1 to 5 thereof, the invention, according to the illustrated embodiment shown therein, comprises an outer tubular casing 10, of elongated oval cross-section, but which may if desired be of any other suitable cross-section, and formed of metal, plastic material, or other suitable substance. A slot 11 is provided in its upper side near one end for cooperation with detent retaining means provided in the clip member.

The clip member is in the general form of a split tube open at both ends, and in the illustrated embodiment consists of upper and lower clamping jaws 12 and 13 integrally connected by a longitudinal bend, there being a longitudinal split opposite the bend. The material from which the clip member is formed is resilient so that in the open position, as shown in Fig. 2, the jaws will spring open to a limited extent.

The cross-section of the clip member is such that when engaged in the tube it will fit the inner surface thereof, and clampingly engage about the eraser rubber element, as will presently more fully appear. The jaws 12 and 13 are respectively provided with transversely disposed projecting ribs 14 and 15, shown opposite each other, for cooperative engagement in the opposed grooves 16 and 17 provided in spaced rela-

tion along the upper and lower surfaces of the eraser rubber element 18, the cross-sectional shape of which is such as to fit snugly within the clip member when the latter is in its contracted inserted relation in the tubular casing 10. Upon the forward ends of the jaws 12 and 13 there are provided flanges 19 and 20 respectively for abutment with the forward edge of the tubular casing 10, to limit the insertion of the clip member, and to support the clip member and the eraser rubber element held thereby against inward pressure as the eraser rubber is being used, and upon the jaw 12 at a point between the abutment flange 19 and the inwardly projecting rib 14 there is provided an outwardly projected detent boss 21, adapted to snap into engagement with the slot 11 of the tubular casing 10 to yieldably retain the clip member against outward removal. This detenting action of the boss 21 is made possible through the yieldability of the eraser rubber 18, and which also permits the clip member to be readily removed by pressing together the lip flanges 19 and 20 to allow the boss 21 to disengage from the slot 11. The rearward edge of the jaw 12 is inclined forwardly from the rearward edge of the jaw 13, as at 22, so as to facilitate the insertion of the clip member in the tubular casing 10, it being only necessary to fit the rearward edge of the lower jaw 13 into the tubular casing 10, and thereupon the upper jaw is automatically closed as the clip member is pressed into the tubular casing, as indicated in Fig. 3, the edge 22 acting as a cam to close the jaw 12 and gradually press it into tight clinching engagement with the eraser rubber. In the operative relation as shown in Fig. 4 the ribs 14 and 15 engage opposed grooves 16 and 17 in the eraser rubber and thereby effectually retain the position of the eraser rubber. When it is desired to renew the point of the eraser rubber, the clip member is disengaged and the eraser rubber is extended the distance of the spacing between the grooves so as to engage the ribs 14 and 15 in the next pair of grooves 16 and 17.

In Figs. 6 to 11 I have illustrated a modified form of the invention, which is of circular cross-section, and in which the circular cross-section tubular casing 10^a has a pencil or crayon element 23 provided in one end and an eraser rubber element 18^a provided in the other end. In this case the tubular casing 10^a is provided adjacent each end with a pair of diametrically opposed slots 24—24, and split tubular clip members of identical form are inserted in each end, these each comprising an upper jaw 12^a, a lower jaw 13^a, and opposed inwardly projected ribs 14^a and 15^a respectively provided upon the jaws. Outwardly pressed diametrically opposed bosses 25—25 are provided adjacent the forward edges of the jaws 12^a and 13^a, which engage the slots 24—24 of the casing to limit the insertion of the clip member and to act as finger grips to permit of convenient removal. It will be noted that the arrangement of the bosses 25—25 in the slots 24—24 eliminates any forward projecting means at the end of the casing. The rearward edge 22^a of the upper jaw 12^a is inclined forwardly, and which edge in this cylindrical form of clip member is substantially spirally shaped and blends into the rearward edge of the lower jaw, the function of this edge being the same as the function of the edge 22 of the first embodiment to automatically close the

jaws as the retaining member is inserted in the tube.

For the purpose of securing the pencil or crayon element 23 there is provided upon the inner surface of the clip member a rubber lining member 26 which protects the surface of the pencil or crayon element 23 against abrasion and breakage. This element 23 is provided with a series of circumferential relatively shallow grooves 27, corresponding in function to the grooves 16 and 17 of the eraser rubber element 18 in the first embodiment, but which in the case of the circular cross-section preferably extend entirely around the element. As shown clearly in Fig. 6, the rubber lining member 26 directly engages the surface of the pencil or crayon element under pressure created by the squeezing together of the clip member when it is inserted in the tubular casing 10^a, the rubber in relation to the ribs 14^a and 15^a being pressed into the groove 27 in register therewith to thereby effectually retain the pencil or crayon element against movement. The eraser rubber element 18^a retained in the other end of the tubular casing 10^a is also provided with circumferential spaced grooves 28, so that such grooves will be engaged by the ribs 14^a and 15^a in any position of rotation of the eraser element.

In Fig. 12 I have shown a further modification in which the eraser rubber element 18^b is provided with grooves 16^b and 17^b in its opposed surfaces, which are in staggered relation to each other, so that thickness of the rubber is only decreased in the region of the grooves by the depth of one groove. The retaining projection rib 15 of the jaw 13 is rearwardly offset with respect to the rib 14 of the upper jaw 12, so as to register with the staggered grooves in the eraser rubber element.

The spaced grooves in the rubber eraser element in addition to their retaining function also provide a more effective erasing surface due to the presence of the transverse edges of the grooves upon the projected erasing end.

I have illustrated and described preferred and satisfactory embodiments of my invention, but it will be understood that changes may be made therein, within the spirit and scope thereof, as defined in the appended claims.

Having thus described my invention what I claim and desire to secure by Letters Patent is:

1. In a holder for a strip of gradually usable material such as eraser rubber, pencil, or the like, a tubular casing member having an open end, a clip member for clampingly engaging said strip insertable in said open end of said casing member, said clip member being longitudinally split and open at both ends whereby the material may extend in unlimited length longitudinally beyond said open ends and having a diagonal rear edge extending forwardly to one edge of said split, said clip member adapted upon insertion in said casing member to cooperatively engage said strip to retain it against longitudinal movement.

2. In a holder for a strip of gradually usable material such as eraser rubber, pencil, or the like, a tubular casing member having an open end, a clip member for clampingly engaging said strip insertable in said open end of said casing member, said clip member being open at both ends whereby the material may extend in unlimited length longitudinally beyond said open ends, a rubber lining member disposed between said clip member and said strip, said clip mem-

ber adapted upon insertion in said casing member to compress said lining member to retain said strip against longitudinal movement.

3. In combination, a holder and a strip of gradually usable material such as eraser rubber, pencil, or the like, having spaced groove means, said holder comprising a tubular casing member having an open end, a clip member for clampingly engaging said strip insertable in said open end of said casing member, said clip member 10

being open at both ends whereby the material may extend in unlimited length longitudinally beyond said open ends, a rubber lining member disposed between said clip member and said strip, said clip member adapted upon insertion in said casing member to compress said lining member to project into said groove means of said strip to retain it against longitudinal movement.

MAX VOGEL.
